UNITED STATES PATENT OFFICE.

WILLIAM F. MERRILL, OF BROOKLINE, MASSACHUSETTS, ASSIGNOR TO LIBRARY
BUREAU, OF CAMBRIDGE MASSACHUSETTS, A CORPORATION OF NEW JERSEY.

PAPER-FASTENER.

1,112,637.

Specification of Letters Patent.

Patented Oct. 6, 1914.

Application filed February 10, 1913. Serial No. 747,294.

To all whom it may concern:

Be it known that I, WILLIAM F. MERRILL, a citizen of the United States, and resident of Brookline, in the county of Norfolk and State of Massachusetts, have invented new and useful Improvements in Paper-Fasteners, of which the following is a specification.

This invention relates to paper fasteners of the kind by which a number of sheets of paper may be detachably bound together for filing purposes, and consists in a two piece fastener containing the novel and improved features of construction hereinafter described and particularly pointed out in the claims.

In the accompanying drawings which illustrate a paper fastener embodying the invention,—Figure 1 is a plan view of one of the two pieces, of which the fastener is composed, namely, the base piece; Fig. 2 is a plan view of the other of the two pieces, namely, the washer; Fig. 3 is a top plan view of the fastener assembled and in operative position; Fig. 4 is a bottom plan view of the assembled fastener; Fig. 5 is a longitudinal section of the assembled fastener; Fig. 6 is a cross section on line 6—6 of Fig. 1; and Fig. 7 is a cross section on line 7—7 of Fig. 2.

The base consists of a relatively long and narrow plate *a* of sheet metal, having formed integral therewith the lengthwise extending binding arms *b*, one at each end. The base *a* is made substantially inflexible under the ordinary conditions of use by the longitudinal stiffening ribs *c*, which are struck up from the metal of the base, while the arms *b* are flexible for the purpose hereinafter described. At the ends of the base *a* are the short flexible fastening prongs *d* by which the base may be secured to the outside or cover sheet of the bound sheets. Said prongs *d* are made integral with the base and arranged beside the binding arms *b*, as shown.

The washer *e* consists of a long and narrow plate of sheet metal, provided with two slots or apertures *f*, near its ends, spaced apart substantially the same distance as the distance between bases of the arms *b*. Said washer also has one or more longitudinal stiffening ribs, *g* struck up from the metal and extending between the apertures *f*.

In use, the base *a* is applied to the outside

or cover sheet, by bending up the binding arms *b* and the prongs *d* at right angles to the base along the dotted lines *h* (Fig. 1), passing them through the sheet either by previously preparing slits for the purpose, or by piercing the sheet with the pointed ends of arms *b*, and the ends of prongs *d*, and then bending and clenching the prongs *d* down on the outside or cover sheet, as most clearly shown in Fig. 5. The base will thereby be secured to the under side of the cover sheet by the prongs clenched on the upper side of the sheet, and the arms *b*, will stand upright from the cover in position to receive other sheets and the washer. The cover sheet and several additional sheets are indicated by *A*. To apply the washer, the arms *b* are inserted through apertures *f* and the washer slipped down on the arms *b* as far as it will go, and the flexible binding arms *b* are then bent outwardly or inwardly (preferably the former) flat on the top sheet, thus securely binding the sheets *A* together between the base *a* and washer *e*.

I claim:

1. A paper fastener comprising a relatively long and narrow base having a narrower flexible binding arm integral with the base extending in a line from each end thereof and in the plane of the base, said arms adapted to be bent at right angles to the base at their junction therewith, a pair of integral flexible fastening prongs shorter than said arms projecting from each of said base ends on opposite sides of and parallel with said arms adapted to be folded on lines continuous with the folds of said arms and pressed flat upon the base to secure the latter to a cover sheet, and a narrow washer longer than the base having apertures near its ends through which said binding arms are passed to be afterward bent laterally over the washer.

2. A paper fastener comprising a relatively long and narrow base provided with longitudinal stiffening ribs extending nearly to the ends thereof, an integral flexible binding arm narrower than said base projecting from each end lengthwise of the base and adapted to be bent at right angles thereto, a pair of straight narrow flexible fastening prongs projecting integrally from each base end on opposite sides of the binding

arm and shorter than said binding arm adapted to be folded on lines continuous with the folds of the binding arms and pressed flat upon the base to secure the latter to a cover sheet, and a washer longer than the base having an aperture near each end through which said binding arms are adapted to pass and be afterward folded over on the washer, said washer being stiff-

ened by a central projecting rib extending 10 longitudinally between said apertures.

Signed by me at Boston, Massachusetts, this 5th day of February, 1913.

WILLIAM F. MERRILL.
